United States Patent Office

Des. 191,704
Patented Nov. 7, 1961

191,704

CHAIR

Bernard H. Stauffer, 1700 Valencia Mesa,
Fullerton, Calif.

Filed May 22, 1959, Ser. No. 56,026

Term of patent 14 years

(Cl. D15—1)

FIG. 5.

FIGURE 1 is a front perspective view of a chair embodying my new design;

FIGURE 2 is a side elevational view;

FIGURE 3 is a rear elevational view;

FIGURE 4 is a sectional view taken along line 4—4 of FIGURE 3; and

FIGURE 5 is a bottom plan view.

I claim:

The ornamental design for a chair, as shown.
